UNITED STATES PATENT OFFICE.

JOSEF DENK, OF VIENNA, AUSTRIA-HUNGARY.

COFFEE-MAKING MACHINE.

SPECIFICATION forming part of Letters Patent No. 555,500, dated March 3, 1896.

Application filed June 1, 1895. Serial No. 551,417. (No model.) Patented in Austria April 23, 1894, No. 62,768, and in Hungary April 23, 1894, No. 95,372.

To all whom it may concern:

Be it known that I, JOSEF DENK, a subject of the Emperor of Austria-Hungary, residing in Vienna, Austria-Hungary, have invented 5 certain new and useful Improvements in Coffee-Making Machines, (patented in Austria, No. 62,768, and in Hungary, No. 95,372;) and I do hereby declare the following to be a full, 10 clear, and exact description of the invention, such as will enable others skilled in the art to which it appertains to make and use the same, reference being had to the accompanying drawings, and to letters of reference marked thereon, which form a part of this specification. 15

The object of my invention is to provide a coffee-making machine of simple, strong and durable construction, easily handled and reliable in operation.

20 The invention consists in the improved coffee-making machine, in a certain flexible locking mechanism and in the combination and arrangements of the various parts thereof, substantially as will be hereinafter more fully 25 described and finally embodied in the clauses of the claim.

Referring to the accompanying drawings, in which like letters of reference indicate corresponding parts in each of the several views, 30 Figure 1 is a central section through my improved device; Fig. 2, an enlarged detail view of a certain coffee-receptacle, and Fig. 3 an enlarged top plan view of a certain seat for the said coffee-receptacle hereinafter more 35 fully described.

In said drawings, A represents a pot, with lid B provided with an air-hole B'. Said pot is removably suspended in a yoke or frame C' secured to base D. In a central recess of said 40 base is arranged the heating device E with handle F, all as in ordinary coffee-making machines.

The pot A is divided by the horizontally-arranged partition-plate b into an upper and 45 lower receptacle a and c, (the upper one being provided near its bottom with an outlet-cock a',) but which are in communication with each other by means hereinafter described. The partition b is provided with a centrally-ar- 50 ranged and upwardly-extending cylinder or cone b', provided at its top with a flange b², having a series of two or more recesses b³, as

clearly shown in Fig. 3 of the drawings. The flange b² of said central cylinder or cone forms the seat for the coffee-receptacle d, provided 55 at its under side with an annular shoulder d' adapted to fit into the top of said cylinder or cone b'. To the side or to the under side of the coffee-receptacle d are secured in any desired manner a series of substantially rectangular springs adapted to pass with their horizontally-arranged portion through the recesses b³ of the flange b², and after being turned with the receptacle d out of alignment with said recesses, to bear against the under 60 side of said flange and thus prevent the entire withdrawal of the receptacle d from the cylinder or cone b'. 65

In the center of the bottom of the receptacle d is secured a tube f extending downward 70 to about the bottom of the lower receptacle c, and is provided with a series of perforations f' opening into the receptacle d.

The upper portion of the tube f terminates 75 into a conical-shaped stem adapted to receive the neck of the hooded sieve h, covering the openings f' in tube f and also a portion of the bottom of the said receptacle. The top portion of the stem is threaded, as at g, and adapted to receive a nut m, secured in the 80 center of the lid i, which latter is provided with a series of small perforations and fits closely on the receptacle d.

A strainer k, made of flannel, lint or any other suitable material, is placed between the 85 lid i and the receptacle d, as shown in Fig. 1.

In operation the lower receptacle is filled with water, ground coffee placed into the receptacle d, the strainer k and the perforated lid placed in position. The receptacle d is then 90 placed on its seat—that is, on the flange b² of cone b'—and is then turned to one side until the rectangular springs e engage the under side of said flange. The pot A is then covered by the lid B and the heating device E 95 started. The water will soon begin to boil and by the pressure of the generated steam will be forced through the tube f and its openings f' (and also sieve h) into the receptacle d, where it is thoroughly mixed and infused 100 with the ground coffee, which infusion is forced by the water following through the strainer k and perforated lid into the upper receptacle, a, of the pot, from where it can

be discharged through cock α' into glasses, cups, &c.

The above-described coffee-making machine has, on account of its flexible spring-locking mechanism, a great advantage over all other coffee-making machines, as an explosion or bursting of the pot is impossible. Should the pressure in the pot get too great, the receptacle d is lifted off its seat by said excessive pressure sufficiently far to allow the surplus of steam to escape, and is then by the action of the angular springs returned to its normal position.

Having thus described my invention, what I claim as new, and desire to secure by Letters Patent, is—

1. In a coffee-making machine, a pot, a partition dividing said pot into an upper and lower receptacle, a central cone or cylinder rising from said partition and provided at its top with an annular flange having a series of recesses, a coffee-receptacle provided at its under side with an annular shoulder to fit on and into the top of said cone, a series of angular springs depending from said receptacle and adapted to bear with their horizontally-arranged portions on the under side of said annular flange and thus to form a flexible locking mechanism, said annular flange, a tube in the bottom of the coffee-receptacle, and extending downward into the lower receptacle of the pot and provided with a series of perforations opening into the said coffee-receptacle, a strainer on said receptacle and a perforated lid on said strainer, all said

parts substantially as and for the purposes described.

2. In a coffee-making machine, a pot, a partition dividing said pot into an upper and lower receptacle, a central cone or cylinder rising from said partition and provided at its top with an annular flange having a series of recesses, a coffee-receptacle provided at its under side with an annular shoulder adapted to fit into the top of said cone, a tube in the bottom of the coffee-receptacle and extending downward into the lower receptacle of the pot and provided with a series of perforations opening into said coffee-receptacle, a cone-shaped stem at the upper end of said tube, a perforated hooded sieve provided with a conical-shaped neck arranged on said stem and covering the perforations in the tube and a portion of the bottom of the receptacle, a strainer on said receptacle, a lid on said strainer, and a series of rectangular springs depending from the receptacle and adapted to engage with their horizontally-bent portions the under side of the flange of the central cone and thus to form a flexible locking mechanism, all said parts, substantially as and for the purposes described.

In testimony that I claim the foregoing I have hereunto set my hand this 6th day of May, 1895.

JOSEF DENK.
